UNITED STATES PATENT OFFICE

JOHN R. GAMMETER, OF AKRON, OHIO, ASSIGNOR TO A. G. SPALDING AND BROS., A CORPORATION OF NEW JERSEY

METHOD OF MAKING BALLS

Application filed April 26, 1927. Serial No. 186,695.

This invention relates to balls comprising an inner compression element held under compression by an outer tension element, as in the case of golf balls, the strained condition of the two elements serving to give the ball as a whole a high coefficient of elasticity and thus to provide for a quick reflexing of the surface of the ball when the ball is struck, so that the full elastic reaction of the ball, or a large part of it, takes place while the ball is still in contact with the club, for high velocity of the ball, and preferably before the ball has so changed its position with relation to the club as to cause the reflexing of the ball to spoil the accuracy of the shot.

My present invention in some of its phases is an improvement upon that of my copending application Serial No. 186,694, filed concurrently herewith.

The chief objects of my present invention are to provide a highly serviceable ball, such as a golf ball or a tennis ball, at low cost; to provide a highly symmetrical ball as to the distribution of its weight; and, more specifically, to provide for molding a fluid-containing ball-structure to a size smaller than that which it assumes when in an uncom-pressed condition prior to the molding opera-tion.

Of the accompanying drawings:

Fig. 1 is a vertical, medial section of apparatus embodying and adapted to carry out my invention as applied to golf balls, the mold constituting a part of the same being shown in open condition.

Fig. 2 is a similar view showing the mold in nearly closed condition.

Fig. 3 is a vertical, medial section of a cov-er mold employed in the practice of my in-vention in its preferred form.

Fig. 4 is an elevation, with parts sectioned and broken away, of a pressure chamber such as that shown in Fig. 2, with the mold and the work therein, representing the pre-fered form of my invention.

Fig. 5 is a section of the finished ball of Fig. 4.

Referring first to Figs. 1 and 2, the golf ball there shown comprises a resilient core or com-

pression member 10 of vulcanized, soft sponge-rubber and a cover 11 thereon, the cover preferably being of balata or gutta percha or a mixture of those and other substi-tutes such as is commonly employed for golf ball covers.

The ball is initially formed of a size sub-stantially larger than the size to which it is later to be molded and consequently larger than the cavity of the mold, consisting of sec-tions 12 and 13, shown in Figs. 1 and 2, with the result that when the ball at atmospheric pressure is placed upon the lower mold sec-tion 13, as shown in Fig. 1, it is too large to seat therein.

To produce the ball in the condition there shown the core member 10 is first molded and vulcanized, with a suitable blowing agent in-corporated in the compound to produce the sponged condition, and the cover 11 is then applied to the vulcanized sponge core, either by applying hemispherical or other shells of the covering material to the core and joining them by pressure or by rolling the core upon a surface thinly covered with the covering material in a warm condition to cause it to pick up the material, or in any other suitable manner. In either case the cover may be given a smooth and impervious exterior, if de-sired, by a molding operation prior to the in-troduction of the ball to the apparatus of Fig. 1.

Before the ball is placed upon the mold sec-tion 13, however, as shown in Fig. 1, if a smooth-surfaced ball is to be made, the cover preferably is formed with one or more small indentations or grooves such as those shown at 14, 14, at the part thereof which is to rest up-on the rim of the mold cavity, so that fluid pressure may be equalized upon all parts of the ball including that extending into the lower mold section.

The lower mold section 13 is detachably mounted in determinate position upon the floor of a pressure chamber 15 and the upper mold section 12 is detachably mounted, by means of a dove-tail rib 16 formed thereon, upon a head 17 in which is swiveled the lower end of a screw 18 which is threaded through the cover 19 of the pressure chamber and is

provided at its upper end with a hand-wheel 20.

The mold section 12 is formed at each end with a guide rib such as the rib 21 adapted to run in a complementary groove formed in the wall of the chamber, to prevent the mold section from turning with the screw 18 and to assure registry of the two mold sections. Vent apertures, such as those shown at 12^a, 10 13^a, may be formed in the mold sections.

The pressure chamber is provided with a water inlet 22 and outlet 23 and with an air inlet 24.

When the ball has been formed and mounted upon the lower mold section 13 as shown in Fig. 1, the cover 19 of the pressure chamber carrying the upper mold section 12, is placed and secured upon the chamber with the upper mold member in the position there shown.

The apparatus or at least the mold sections and the ball itself are suitably heated, as by passing hot air or an inert gas in a heated condition through the chamber by means of the inlet 24 and outlet 23, to soften the cover of the ball and to provide for its proper conformance to the wall of the mold-cavity in the subsequent molding of the ball. Alternatively the mold-sections may be electrically heated or heated otherwise before they are placed in the chamber, and the ball may be heated apart from the apparatus before it is introduced thereto.

With conditions as shown in Fig. 1 and with the cover of the ball suitably softened, a fluid, preferably air or an inert gas, is conducted into the chamber, the connections 22 and 23 being closed, at a sufficiently high pressure to cause the ball to contract in size so that it fully seats in the cavity of the lower mold section, the impervious but soft cover 11 contracting in circumference and transmitting the force of the pressure fluid to the sponge rubber core and causing the air or gas contained in the cells thereof to be compressed and the rubber of the cell walls to be put under strain.

When the ball has thus contracted and fallen into the lower mold cavity the upper mold section is closed upon the ball by turning the hand-wheel 20, after which the fluid pressure in the chamber is released, whereupon the stresses in the ball, without being relieved to any great extent, cause the ball to expand and completely fill the mold cavity and to take the form thereof.

While the mold remains closed a cooling fluid such as water is passed into or through the chamber, cooling the mold and causing the cover 11 of the ball to harden or set. Alternatively the cover may be composed of a vulcanizing compound and may be vulcanized by heat received by it from the mold.

When the cover of the molded ball has thus been set, by cooling or by vulcanization or otherwise, the chamber and the mold are opened, the finished ball is removed, and the

operation as described is repeated upon another ball.

Upon the opening of the mold and the removal of the ball therefrom the set cover 11 sustains the force of the compressed core and is thus put under high tension, and the compressed core and the tensioned cover function together to give the ball as a whole the desired high coefficient of elasticity, in somewhat the same manner that a pair of leaf springs flexed in opposition to each other show less deflection under a given load than either of them alone would show.

The comparatively inextensible character of the cover material, when such a material is used, may prevent its elasticity from being an important factor in the resilience of the ball under a heavy blow, and yet the cover may normally hold the core under such compression that the distortion of the core will be small and its reflexing very quick when the ball is struck.

In the preferred practice of my invention illustrated in Figs. 3 and 4 hemispherical shells 25, 26 of the cover material are molded directly in the mold sections 12, 13 by means of a double-acting male die 27 and the mold sections with the shells remaining therein are transferred to the pressure chamber 15 as shown in Fig. 4.

The male die is formed with a fluid passage 28 for passing compressed air therethrough to separate it from the molded shells and leave the latter in the respective mold sections, a poppet valve 29 being provided at each terminus of the passage to prevent flow of the plastic material thereinto in the molding operation although permitting the fluid to pass outward from the male die member. Molding pins 30, 30 project outward from the centers of the respective poppet valves and are adapted to project into the vent apertures 12^a, 13^a of the mold sections, for molding vent apertures 25^a, 26^a (Fig. 4) in the shells.

The mold section 13 may be provided with means, such as the cam latches 34, 35, adapted to engage automatically in detent recesses 36, 37 in the section 12, for securing the sections together.

After the lower mold section 13 with the shell 26 therein has been mounted in the chamber 15 a suitable compressible core, here shown as consisting of joined hemispherical bodies 31, 32 enclosing a weighting sphere 33 of lead, heavily compounded rubber or the like, is mounted upon the shell 26 as shown, after which the cover of the chamber, carrying the mold section 12 with the shell 25 therein, is mounted upon the chamber, pressure fluid such as compressed air is admitted to the latter to compress the core so that it shrinks and fully seats in the lower shell 26, the upper mold section is closed down to enclose the core completely in the shells and the pressure in the chamber is then so reduced as

to permit the core to expand and fill the cover, the shell being vented through the apertures 25^a, 26^a. The shells are then caused to weld together, by simply heating and cooling the 5 mold sections if the cover shells are of heat plastic but non-vulcanizing material, or by vulcanizing them together if they are of vulcanizable material.

The heating and cooling or the vulcanization may be effected in this same chamber, 10 if desired, or the mold sections with the work enclosed therein may be secured by suitable means, such as the cam latches 34, 35, while they are in the pressure chamber and then 15 removed to other apparatus for the cover-welding operation.

The vent apertures 25^a, 26^a are closed by the force of the expanding core when the cover shells are heated.

20 The compressible core may be formed in numerous alternative ways. For example it may consist of a spherical shell held in a stretched condition by an elastic pressure fluid contained therein, so that it may be compressed to or slightly beyond its unstrained size without buckling, or it may consist of a spherical winding of scrap thread rubber upon a suitable weighting sphere such as a lead or heavily compounded rubber ball, and 25 30 enclosed in suitable sealing means such as an impervious rubber envelop or a winding of comparatively wide rubber tape.

A low temperature accelerator is of course employed where the cover is to be vulcanized, 35 in order to avoid heating the core material to a temperature such as to relieve the strains therein.

Many other modifications are possible within the scope of my invention as defined in the 40 appended claims.

I claim:

1. The method of making a ball which comprises molding an outer tension element upon an inner compression element while holding 45 the latter under compression by subjecting it to super-atmospheric external fluid pressure.

2. The method of making a ball which comprises forming a compressible, fluid-containing ball member, compressing said member to a smaller size by subjecting it to a super-atmospheric external fluid pressure, and enclosing it in a mold while it is so held to small size.

55 3. The method of making a ball which comprises forming an elastic envelop, distending the same by internal pressure of an elastic fluid, reducing the size of the distended envelop and increasing the pressure of the fluid therein by subjecting it to a preponderating external fluid pressure, and molding a cover upon the envelop while so holding it to reduced size.

65 4. The method of making a ball which comprises forming an envelop, distending the same by internal pressure of an elastic fluid,

reducing the size of the distended envelop and increasing the pressure of the fluid therein by subjecting it to a preponderating external fluid pressure, enclosing the envelop in a mold while it is so held to reduced size, and permitting it to expand in the mold by reduction of the external fluid pressure. 70

5. The method of making a ball which comprises reducing the size of a ball-forming body by applying external fluid pressure thereto and enclosing the body in a mold 75 while it is thus held to small size.

6. The method of making a ball which comprises forming a compressible core, reducing the size of the core by applying external fluid pressure thereto, enclosing the core in covering elements held in sections of a mold while the core is thus held to small size, reducing the pressure of the external fluid and thereby permitting the core to expand in the mold, and uniting the covering elements upon the core while they remain in the mold. 80 85

7. The method of making a ball which consists in forming a sponge rubber core, applying thereto an impervious layer of deformable material, reducing the size thereof by surrounding it with fluid under pressure, and fixing a strain resisting cover thereon while so held to reduced size. 90

In witness whereof I have hereunto set my hand this 22nd day of April, 1927.
